UNITED STATES PATENT OFFICE.

STACY B. HASELTINE, OF CHICAGO, ILLINOIS, ASSIGNOR TO WILLIAM H. MINER, OF CHAZY, NEW YORK.

DOOR-OPERATING MECHANISM FOR REFRIGERATOR-CARS.

1,187,910.

Specification of Letters Patent. Patented June 20, 1916.

Application filed May 10, 1915. Serial No. 27,606.

To all whom it may concern:

Be it known that I, STACY B. HASELTINE, a citizen of the United States, residing at Chicago, in the county of Cook and 5 State of Illinois, have invented a certain new and useful Improvement in Door-Operating Mechanism for Refrigerator-Cars and the like, of which the following is a full, clear, concise, and exact description, reference being had to the accompanying drawings, forming a part of this specification.

This invention relates to improvements in door operating mechanism for refrigerator cars and the like.

15 An object of the invention is to provide a door operating mechanism for refrigerator cars wherein the shaft of the mechanism is given a rolling movement parallel with the face of the door, and wherein means are 20 provided for lifting the shaft so that the lower end thereof may be raised flush with the lower edge of the door, and thus permit the latter to be readily swung out over a platform.

25 Another object of the invention is to so arrange the means for lifting the shaft that the shaft is lifted by the operating lever at the end of the opening movement, thus minimizing the number of operations.

30 The invention furthermore consists in improvement in the parts and devices and in the novel combinations of the parts and devices herein shown, described or claimed.

In the drawing forming a part of this 35 specification, Figure 1 is a side elevation of a portion of a refrigerator car, showing the door thereof and my improvements in connection therewith. Fig. 2 is a horizontal sectional view taken substantially on the 40 line 2-2 of Fig. 1. Fig. 3 is an enlarged vertical sectional view taken on the line 3-3 of Fig. 1. Fig. 4 is an enlarged side elevational view of the door operating mechanism proper and showing the position 45 of the parts at the end of the opening movement and prior to the lifting of the shaft, so that it may clear a platform. Fig. 5 is a detailed view of a portion of the operating shaft, the operating lever and the fulcrum showing the position of the parts after the shaft has been elevated. Fig. 6 is a vertical sectional view taken on the line 6-6 of Fig. 5, and Fig. 7 is a sec-

tional view taken on the line 7-7 of Fig. 1 and showing also in dotted lines the position of the parts at the end of the turning 55 rolling movement of the shaft.

In said drawing 10 and 11 designate hinged refrigerator car doors, the latter being the last one to be closed. Said doors 60 are provided with bevel meeting edges as indicated at 12 in the usual manner and suitable packings are provided on said meeting edges and also around the other edges of the door and door frame. As is customary, the operating shaft is mounted on the last door to be closed, that is, the door 11 in the structure shown. In accordance therewith, I provide an operating shaft designated by the reference A and, as 70 shown, the same comprises an intermediate connecting rectangular bar 13, end castings 14-14 and gear wheel castings 15-15. Each end piece 14 is forked as indicated at 16 and in addition is provided with a portion 17 polygonal in cross section and an 75 extreme outer cylindrical portion 18. Each gear wheel 15 is provided with a gear 19 proper and a hollow sleeve or hub 20, the interior of which is polygonal in cross 80 section and is arranged to fit and slide upon the polygonal section 17 of the corresponding end member. Secured to the lintel and threshold of the door opening are keepers 21 and 22 each of 85 which is provided with inclined camming surfaces 23 and 24 forming therebetween a cross or guide way for the cylindrical ends 18 of the operating shaft.

The operating shaft is supported, and 90 guided by the upper and lower guide plates 25-25, each of which is in the form of a single casting and comprises a rear wall 26, an inclined front wall 27 and a longitudinally extending rack 28, the casting being open in front of the rack and below the inclined wall 27. With this construction I am enabled to utilize a single piece casting for each guide plate since the gear piece 15 can be inserted in the manner indicated in 100 dotted lines in Fig. 3, that is, by inserting it at an angle and then swinging it around to the vertical so that the gear 19 proper will then mesh with the rack 28.

In order to roll the shaft a hand lever 29 105 is provided which is pivoted to the

shaft as indicated at 30, the lever 29 being forked and straddling the shaft as clearly indicated in Fig. 3. One of the forks of the lever 29 is provided with a 5 cam portion 31 which, when the lever is in the position shown in Fig. 1 is on the outer side of the shaft, but when the lever is swung through an arc of 180° to the position shown in Figs. 4, 5 and 6, is on the inner 10 side of the shaft. This cam 31 is adapted to coöperate with a fulcrum casting 32 having a curved depression or notched member 33, said casting 32 having also an upstanding guide flange 34.

15 The operation is as follows: Assuming the parts in the position shown in Fig. 1, the door is opened by grasping the lever 29 and swinging it through an arc of 180°. This causes the shaft A to both rotate and 20 roll, the latter movement being occasioned by the inter-engagement of the gears and racks. As this rolling of the shaft takes place, the cylindrical ends 18-18 will travel up the inclined camming surfaces 23 25 of the keepers and thus force the door 11 open to the dotted position shown in Fig. 7. If it is now desired to lift the shaft so that the lower cylindrical end 18 will clear an 30 adjacent platform as indicated at 40 in Fig. 3, the hand lever 29 is depressed, the cam 31 engaging the fulcrum casting 32 and thus lifting the shaft A. The depression 33 is so arranged that the cam 31 will fall thereinto when the lever 29 is depressed. And it is 35 located directly beneath the axis of the pivotal connection between the hand lever and shaft. With this arrangement, after the shaft has been elevated, it will automatically be retained in such elevated position, 40 due to the weight of the lever 29 in its depressed or downward position. To close the door, the reverse of the above described sequence of operations is employed, the door being forced to closed position by 45 the cylindrical ends 18 engaging the inclined camming surfaces 24 of the keepers.

Although I have herein shown and described what I now consider the preferred embodiment of my improvements, yet I am 50 aware that changes and modifications may be made without departing from the spirit of the invention, and I contemplate all such changes and modifications as come within the scope of the claims appended hereto.

55 I claim:

1. In a device of the character described, the combination with a member having a door opening, a hinged door, and keepers secured to such member adjacent the door opening, of means for opening and closing said door including a rotatable shaft, the ends of which are extended beyond the edges of the door and adapted to engage with said keepers, and coöperating devices on the 60 door and shaft, causing the latter to roll

transversely of the door when rotated, said shaft being longitudinally slidable relatively to said door, whereby one end thereof may be made flush with the adjacent edge of the door.

2. In a device of the character described, the combination with a door, of a rolling shaft, bearing for said shaft and arranged to permit it to roll when rotated, a rack on said door, a gear secured to said shaft and meshing with said rack, the ends of the shaft being extended beyond the edges of the door and adapted to coöperate with keepers, and means for lifting said shaft vertically to thereby bring the lower end 70 thereof flush with the lower edge of the door.

3. In a device of the character described, the combination with a swinging door, of an operating shaft mounted thereon and 75 adapted to roll for a limited distance back and forth, said shaft being also axially movable, a lever pivoted to said shaft for rotating the same, and a fulcrum on said door with which said lever is arranged to 80 coöperate when the shaft is at one end of its rolling movement.

4. In a device of the character described, the combination with a hinged door, of an operating shaft, guide plates secured to said 95 door, said plates being provided with racks, gears on said shafts coöperating with said racks and arranged to cause the shaft to roll when the latter is rotated, a lever pivotally connected to said shaft, and a fulcrum member secured to said door, said lever having a projection arranged to engage said fulcrum member when the shaft is rolled to open position, the shaft being elevated when said lever is depressed with said member as a 100 fulcrum therefor.

5. As an article of manufacture, a cast 105 combined guide bearing and rack having a rear wall, a front wall spaced therefrom and a rack formed in said rear wall below the level of the lower edge of the front wall.

6. As an article of manufacture, a cast 115 combined guide bearing and rack having a rear wall, a front wall spaced therefrom and a rack formed in said rear wall, below the level of the lower edge of the front wall, said front wall being outwardly inclined to thereby provide clearance for the insertion of another member.

7. In a device of the character described, the combination with a door, a shaft mounted on said door, means causing said shaft to roll when the same is rotated, an operating lever pivoted to said shaft, a fulcrum casting on said door, the latter having a depression therein, said lever having a projection adapted to engage in said depression when the lever is swung downwardly about said casting as a fulcrum to 125 130

elevate the shaft, the shaft being automatically retained in its elevated position when said lever is so positioned that the projection thereof is in engagement with said depression on the fulcrum casting.

8. In a device of the character described, the combination with a door, of a rolling shaft, bearings for said shaft intermediate the ends thereof and permitting it to roll while being rotated, a rack on said door, and a gear secured to said shaft meshing with said rack, the ends of said shaft being extended beyond the edges of the door and adapted to enter keepers having camming surfaces.

9. As an article of manufacture, a door operating shaft consisting of an intermediate connecting member and end pieces, each end piece having a gear and a cylindrical extreme end portion, the gears being adapted to mesh with racks and said extreme cylindrical end portions being adapted to engage in keepers.

10. In a device of the character described, the combination with a hinged door, of a rolling shaft mounted on said door, bearings near each end of said shaft, said bearings permitting the shaft to roll therein, gears secured to said shaft near the ends thereof and racks on said door coöoperating with

said gears, the ends of said shafts being extended beyond the edges of the door.

11. As an article of manufacture, a door operating shaft comprising an intermediate connecting bar, end castings secured to the ends of said bar, each end casting having a cylindrical extreme end portion and a portion polygonal in cross section intermediate said cylindrical portion and the connecting bar, and a sleeve mounted on each of said portions polygonal in cross section, each having a cylindrical portion forming a journal and a gear.

12. In a device of the character described, the combination with a member having a door opening therein, a hinged door, and keepers secured to said member adjacent the door opening, of means for opening and closing said door, said means including a rotatable shaft the ends of which are extended beyond the edges of the door and adapted to engage in said keepers, and coöoperating devices on the door and shaft causing the latter to roll transversely of the door when said shaft is rotated.

In witness that I claim the foregoing I have hereunto subscribed my name this 28th day of April 1915.

STACY B. HASELTINE,
